CLAIM

(57) The ornamental design for a humidifier, as shown and described.

DESCRIPTION

FIG. 1 is a front, top perspective view of a humidifier, showing my new design;

FIG. 2 is a side perspective view thereof;

FIG. 3 is a rear, bottom perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof;

FIG. 9 is a bottom plan view thereof; and,

FIG. 10 is an enlarged view of the area labeled 10 in FIG. 1.

The dashed lines in the figures illustrate portions of the humidifier that form no part of the claimed design.

The dot-dash-dot broken lines of the humidifier in FIG. 1 illustrate a boundary and cut line of the enlarged view in FIG. and form no part of the claimed design.
